AIR CONDITIONING APPARATUS

William S. Elliott, Pittsburgh, Pa., assignor to
 Elliott Company, Pittsburgh, Pa., a corporation
 of Pennsylvania

Application July 6, 1933, Serial No. 679,213

8 Claims. (Cl. 257—8)

Figure 1 is a diagrammatic side elevation with parts broken away showing one form of apparatus for carrying out my invention; and

Figure 2 is a vertical section on the line II—II
 5 of Figure 1.

My invention relates to a system for conditioning air which will operate under either summer or winter temperatures and enable the air to be kept at any desirable temperature and also 10 preferably at any desirable degree of humidity.

In the drawing, 2 represents a water-treating chamber shown in the form of a cylindrical shell containing a distributing pan 3 in its upper portion, and below it two sets of spray pans 4 and 5, mounted on suitable supports within the shell. The bottom of the chamber 2 forms a water-containing receptacle having a suitable float 6, operating through counterweighted lever 7 upon a connection 8 to control a valve indicated at 9, 15 which regulates the incoming make-up water. The make-up water is supplied to the distributing pan 3 through pipe 10 having a hand valve 11, and a branch 12 leads from pipe 10 to circulating pipe 13, which also has a hand valve 14. 20 The pipe 13 leads to a surface condenser 15, having a vent and valve 15^a. Circulating water passes through the condenser and tubes, thence flows through pipe 16 and thence into the distributing pan 3 when the valve 14 is open and 25 the valve 11 is closed. At the side of the chamber 2 adjacent the lower tray bank is a steam inlet pipe 17, having a hand valve 18. Between the valve 18 and the chamber 2, the pipe 17 is provided with a valve 19, controlled by a connection 20 with a thermostatic device 21, located 30 at any convenient point in the region where it is desired to maintain a constant temperature.

From the upper part of the shell 2 leads a pipe 22 having a hand valve 23 and an automatic valve 40 24, having a connection 25 to thermostatic device 26, also in the region where it is desired to control the air temperature. The pipe 22 leads to thermo-compressor 27, shown as a steam ejector, having steam inlet pipe 28. This thermo-compressor leads to condenser 29, which may be 45 of any desirable type having water inlet 30 and outlet 31.

From the bottom water-containing portion of chamber 2, pipe 32 leads to a pump 33, by which 50 the water may be pumped through pipe 34 or through pipe 35, leading from its outlet. Both these pipes contain hand valves 36 and 37, so that the pump may supply the water to the air-conditioning chamber through either or both of said connections. The air-conditioning cham-

ber, which may be of any desirable type, is shown as a horizontally extending cylindrical shell 38, having a horizontally extending tube bank 40, which tubes connect to end chambers 43 and 44. In the upper part of this shell is a spray section 39, consisting, as shown, of a plurality of larger tubes 41 with perforations in their bottom portions, these tubes connecting the left hand chamber 42 with a right hand chamber 42^a. At the opposite sides of the shell 38 are shown a large 10 air inlet 45 and an air outlet 46. At the bottom of the chamber 38 is a well 47, to collect the water spraying down over the tubes, this well having a pipe 48, leading upwardly and connecting with the pipe 13. The pipe 48 has a hand valve 49 15 and a branch 50 leading into chamber 44 and having a hand valve 51. Pipe 48 is provided with a water leg drain pipe 52 having a hand valve 53.

Assuming that the system is started in summer time, valve 18 is closed and valve 23 and the valve 20 pipe 28 are open. The proper amount of water is supplied through pipe 10 and valve 11, valves 14 and 15^a being closed, and thence to the distributing pan 3 and the tray stacks. During this period, the thermo-compressor 27 is operating to 25 withdraw air and vapors released from the entering water which collects in the lower part of shell 2. When the proper amount of water is collected in chamber 2, the pump 33 is started and the valve 37 being closed, the pump forces the 30 water through pipe 34 and open valve 36 to chamber 42. The water passes down through the spray pipes 41 over the tubes and collects in well 47. At the same time, air to be cooled is rapidly passed over the tubes through connections 45 and 46. 35 During this time, valves 51 and 53 are closed and valve 49 is open. The water collecting in the well will be drawn by the vacuum in the main shell 2 through open valve 49 to pipe 13. During this time, the pipe 17 is closed by hand valve 18. As 40 the temperature in the region of thermostat 26 falls, this thermostat will tend to close the valve 24, and thus reduce the amount of vapor withdrawn by the thermo-compressor and condensed in the condenser 29, thus decreasing the cooling 45 effect on the water; while on the other hand, if the temperature rises, the opposite will be the case.

During cold weather, the valve 14 is open, the valve 11 is closed, the steam valve 18 is open, 50 valve 36 is closed, valves 37, 51 and 15^a are open, and valves 49 and 53 are closed. During such a period, the circulating water flows through pipe 13, thence passing through the condenser 15 direct to the distributing pan 3. As the water 55

passes down over the tray stacks, it is heated by the entering steam and drops as before into the bottom of the shell 2. As the hand valve 23 to the thermo-compressor is closed during such periods, the withdrawal of vapor and air is now through the condenser 15, and the steam is shut off from the connection 28. In this case, the pump 33 forces the heated water through pipe 35 and valve 37 and into chamber 43, whence it passes through the tubes 40 into chamber 44 and is withdrawn through valve 51 to enter pipe 13. The air rapidly passing over these tubes through connections 45 and 46 will therefore be heated. The partially cooled water thence flows back through pipe 13 and pipe 16 and is again heated in the closed circuit.

During such periods of operation, if the temperature tends to rise in the region where a certain air temperature is to be maintained, the thermostatic device 21 will act upon the valve 19 in the steam supply to allow this valve to partly close and thereby decrease the amount of heat supplied to the water. If the temperature tends to drop in such region, the opposite will take place.

If, during such period of operation in cold weather, the humidity of the air is below a desirable range, the valve 36 may be cracked open slightly and the valve 53 opened. This will cause some heated water to pass down in contact with the air and humidify it, and be discharged through pipe connection 52.

The advantages of my invention will be apparent to those skilled in the art, since with one system I am able to condition air at all seasons, whether colder or warmer, simply by manipulating certain control valves. Also, by the same apparatus, I am enabled to humidify the air in colder seasons as required.

Many changes may be made in the form of the apparatus and various parts thereof, without departing from my invention.

I claim:

1. In an air conditioning apparatus, a liquid supply chamber, means for heating the liquid therein when desired, means for cooling the liquid therein when desired, an air conditioning chamber, connections arranged to lead the heated or cooled water from the supply chamber to the air conditioning chamber, and means for feeding the heated or cooled water in different paths through said air conditioning chamber.

2. In an air conditioning apparatus, a liquid supply chamber, means for heating the liquid when desired, means for cooling the liquid when

desired, an air conditioning chamber, connections arranged to lead the heated or cooled water from the supply chamber to the air conditioning chamber, means for feeding the heated or cooled water in different paths through said air conditioning chamber, and connections for admixing a portion of the liquid with the air in the air conditioning chamber when desired.

3. Air conditioning apparatus comprising a liquid treating chamber and an air conditioning unit spaced laterally therefrom, a connection from the chamber to the unit and a connection from the unit to the chamber, means for removing air and vapors from the chamber when it is desired to cool the air, means for heating liquid in the chamber when it is desired to heat the air, and means effective to maintain a continuous circulation of fluid from the chamber to the unit and back again in both cooling and heating periods.

4. The apparatus defined by claim 3 including means for maintaining a constant liquid level in said chamber.

5. Air-conditioning apparatus comprising a liquid-treating chamber, means for heating liquid therein, means for evacuating the chamber to cool the liquid therein, an air-treating apparatus separate from said chamber having an air inlet and an air outlet, and means for circulating liquid from said liquid-treating chamber to the air-treating apparatus, and from the latter to the former, said apparatus having a plurality of paths therethrough whereby the air may be brought in contact with the liquid or merely in heat exchange relation therewith, without actual contact, either to humidify or to dehumidify the air traversing said apparatus, and also to vary the temperature of the air in accordance with the temperature of the liquid supplied thereto.

6. The apparatus defined by claim 5 wherein said means for evacuating the chamber comprises thermo-compressor means connected to said chamber and a condenser connected to said thermo-compressor means.

7. The apparatus defined by claim 5 including thermally responsive means for controlling the operation of said liquid-heating and liquid-cooling means.

8. The apparatus defined by claim 5 wherein the means for heating the liquid in said treating chamber comprises means for supplying steam thereto.

WILLIAM S. ELLIOTT.
